J. H. FOOTE

SHEAVE BEARING HOUSING

Filed Jan. 30, 1922

James H. Fout INVENTOR.

UNITED STATES PATENT OFFICE.

JAMES H. FOOTE, OF CINCINNATI, OHIO.

SHEAVE-BEARING HOUSING.

Application filed January 30, 1922. Serial No. 532,776.

To all whom it may concern:

Be it known that I, JAMES H. FOOTE, a citizen of the United States, residing at the city of Cincinnati, in the county of Hamilton and State of Ohio, have invented new and useful Improvements in Sheave-Bearing Housings, of which the following is a specification.

My invention relates to sheave bearing 10 housings for sash cord pulleys and the like, and more particularly to the form and manner of arrangement of their parts for locking the sheave housing to a mounting frame; the object being to provide a cheaply constructed sheave bearing housing that may be quickly and securely locked to a mounting frame, when positioned therein, without the use of screws or similar securing devices; a further object being to furnish a sheave 20 bearing housing that may be easily released and removed from the mounting frame should occasion require.

These and other objects, I attain by mechanism such as illustrated in the accompanying drawing, in which;

Figure 1 is a view in front elevation of a housing embodying my invention with the sheave removed; Fig. 2, is a view in vertical section taken on the dotted line *a—a* of Fig. 1, the position the sheave would occupy being indicated in dotted lines; Fig. 3, is a view in vertical section taken on the dotted line *c—c* of Fig. 2, looking toward the front; Fig. 4, is a fragmentary view in horizontal section taken on the line *b—b* of Fig. 1, looking toward the lower end of the housing; Fig. 5 is a view in side elevation of a sheave bearing housing embodying the invention, in locked position in a mounting 40 frame, which latter is shown in fragmentary vertical section.

Similar numerals refer to similar parts throughout the several views.

While, for convenience in illustration, I have shown the improved housing as composed of a separate sheet metal face plate connected to separately formed housing walls of sheet metal, it will be understood, that the face plate and housing walls may be formed from a single piece of sheet metal, if preferred.

It will also be understood that, any or all of the parts composing the housing or sheave, may be formed by other means than

sheet metal by well known processes now in general use.

A face plate 1, having a centrally disposed opening 2, and carrying upper and lower rearwardly projecting tongues 3, 4, having flexible pronged extensions 20, 21, and rearwardly extending, medianly positioned flanges 5, 6, to provide spacers, locking and connecting elements, a pair of side walls 7, 8, turned inwardly at their upper and lower ends and adapted, cooperatively, to form an upper cross wall 9 and a lower cross wall 10, a shoulder pin 11 by which the housing parts are maintained in assembled position, and a sheave 12, which may be rotatively mounted on pin 11, constitute substantially, the component parts of my improved sheave bearing housing.

Tongue 3 is provided with side tongues 22—23, and tongue 4 with side tongues 24—25, adapted to fit respectively into slots 26—27, and 28—29, formed in the bottoms of slight depressions 30—31 and 32—33, adjacent the upper and lower ends of walls 7, 8, thus forming complementary interlocking parts for connecting face plate 1 to side walls 7, 8.

An additional connection between these parts may be provided, if desired, by bending outwardly the ends of flanges 5, 6, to form hooks 40—41, and forming slots 42—43, in walls 7, 8, for them to fit into; or, flanges 5, 6, may be welded to walls 7, 8.

Tongue 3 is provided with a flexible extension 20 having outwardly projecting terminal prongs 14—15, adapted for locking engagement with a mounting frame 13, and for a like purpose, tongue 4, is provided with a flexible extension 21, having outwardly projecting terminal prongs 16—17.

Flexible extensions 20, 21, are preferably formed of a rearward continuation of tongues 3, 4, somewhat reduced in width to admit of free outwardly and inwardly bending movement between walls 7 and 8.

These extensions may be formed, however, of separate pieces welded or otherwise connected to tongues 3, 4, if preferred.

In flexible extension 20 of tongue 3 an opening 18, and in flexible extension 21 of tongue 4 an opening 19 is formed by removal of a portion of the metal in a plane slightly beyond that of the rear edges respectively, of side tongues 22—23 and 24—25,

to diminish the resistance of these extensions to bending and facilitate the movement of their respective terminal prongs 14—15 and 16—17, into locking engagement with mounting frame 13, as well as to provide ways for obtaining a purchase upon the outer face 20^a of flexible extension 20 and 21^a of flexible extension 21, to facilitate withdrawal of prongs 14—15 and 16—17, from locked engagement with mounting frame 13, should occasion require.

Side walls 7, and 8 are provided at their upper and lower ends with slots 34—35 and 36—37 for the outwardly and inwardly passage respectively, of prongs 14—15, and 16—17 while undergoing movement into or out of locking engagement with mounting frame 13, and are further provided with centrally disposed circular openings 38, 39, into which the reduced ends 11^a of shoulder pin 11, are adapted to fit.

When assembled, side walls 7, 8, are spaced apart by flanges 5, 6, the hooked ends 40, 41, of which, are fitted respectively into side wall slots 42, 43, by tongues 3, 4, the side tongues 22—23 and 24—25 of which are fitted respectively into side wall slots 26—27 and 28—29, and the flexible extensions of which, 20, 21, are bent inwardly to assume position substantially as shown in Fig. 2, with prongs 14—15, just entering slots 34—35 and prongs 16—17, slots 36—37, by shoulder pin 11, upon which sheave 12 is mounted, and the reduced ends 11^a of which are fitted into side wall openings 38, 39, and by the upper and lower inwardly bent portions of walls 7, 8, which meeting on a median line, form upper and lower cross walls 9, 10.

To secure and maintain the sheave and housing parts in their then relative assembled position, the projecting ends 11^a of shoulder pin 11, are riveted up on the outer sides of walls 7 and 8, which thus become permanently held between the rivet head and shoulder respectively at opposite ends of pin 11.

To position for use, the sheave bearing housing is passed inwardly through an aperture formed in mounting frame 13, for it to fit into, until its inward passage is arrested by face plate 1, which is extended somewhat laterally beyond the walls of the housing, in engagement with the front face of mounting frame 13.

A pointed or wedge shaped tool, for instance a brad awl or a screw driver blade, may then be introduced through face plate opening 2 between sheave 12 and tongues 3, 4, and the flexible extension 20, 21, of these tongues prized or wedged outwardly, thus moving their respective prongs 14—15 and 16—17, outwardly through side wall slots 34—35 and 36—37, into engagement respectively with the upper and lower ends

of the aperture provided for the housing to fit into in mounting frame 13, thus maintaining the housing against retrograde or forwardly movement and locking it in said aperture.

Or, by means of a forked tool having a pair of wedge shaped tines spaced to admit the sheave between them, by a single backwardly movement, prongs 14—15 and 16—17, may be simultaneously moved outwardly into engagement with the mounting frame.

To unlock and remove the housing from the mounting frame, a pointed tool, for instance a brad awl, may be introduced through openings 18, 19, in flexible extensions 20, 21, a purchase obtained with the point upon their outer faces 20^a and 21^a respectively, and extensions 20, 21, prized inwardly until their respective prongs 14—15 and 16—17, have resumed substantially the position shown in Fig. 2.

The housing may then be drawn forwardly out of the frame aperture.

Of course, various modifications and changes in form and material will suggest themselves that may be utilized without any departure from the invention as herein disclosed, and such as well as other modifications need not be illustrated as modifications within the spirit and scope of the invention as shown and pointed out in the claims, will be obvious to those skilled in the art.

What I claim is:—

1. A sheave bearing housing consisting of a sheave, a supporting element to which said sheave is journaled, adapted to fit into an aperture in a mounting frame, a face plate provided with a centrally disposed opening for the passage of the sheave and with means to engage the mounting frame, spacers for the side walls of the supporting element carried by and connecting said face plate to said supporting element, each of a plurality of said spacers being provided with a flexible extension, and means associated with said extension to releasably engage the mounting frame and, in cooperation with the face plate, lock the housing to said frame.

2. A sheave bearing housing comprising a sheave, a supporting element adapted to fit into an aperture in a mounting frame and having side walls between which the sheave is mounted, a face plate laterally extended to overlie a portion of the front face of the mounting frame adjacent said aperture, and having a centrally disposed opening for the passage of the sheave, spacers for, and projecting inwardly between, the walls of the supporting element carried by and connecting said face plate to said supporting element, each of a plurality of said spacers having a rearwardly projecting flexible extension provided with means for

releasable engagement with the mounting frame, and means associated with the supporting element to facilitate said engagement with the mounting frame.

- 5. 3. A sheave bearing housing comprising, a sheave, a supporting element adapted to fit into an aperture in a mounting frame and having side walls between which the sheave is mounted, a face plate with means
- 10 to engage the mounting frame and having an opening for the passage of the sheave, spacers carried by said face plate, for and projecting inwardly between the walls of the supporting element, interlocking parts
- 15 on said spacers and on the walls of the supporting element to lock the face plate to said supporting element, and a flexible extension, projecting rearwardly from, respectively, the upper and lower of said spacers,
- 20 provided with means for engagement with the mounting frame.

4. A sheave bearing housing consisting of a sheave, a supporting element adapted to fit into an aperture in a mounting frame and having side walls to which said sheave is journaled, a face plate adapted to engage the mounting frame and provided with an opening for the passage of the sheave, a plurality of spacers projecting rearwardly between the walls of the supporting element carried by said face plate, interlocking parts on said spacers and on the walls of the supporting element to lock the face plate to said supporting element, and a flexible extension, extending rearwardly from both the upper and lower of said spacers, provided with terminal prongs adapted to engage the mounting frame.

- 5. A sheave bearing housing comprising
- 40 a sheave, a supporting element to seat in an aperture in a mounting frame and having side walls to which said sheave is journaled, a face plate provided with an opening for

the passage of the sheave and with means to engage the mounting frame, a plurality of 45 spacers carried by said face plate and projecting inwardly between the walls of the supporting element, interlocking parts on said spaces and on the walls of the supporting element to lock the face plate to said 50 supporting element, a flexible extension, provided with terminal prongs for engagement with the mounting frame, extending rearwardly from each of a plurality of said spacers, and means to facilitate the passage 55 of said prongs into engagement with said mounting frame.

6. A sheave bearing housing comprising a sheave, a supporting element having side walls to which the sheave is journaled, 60 adapted to fit into an aperture in a mounting frame and provided with means to sustain the thrust of said element against the ends of said aperture, a face plate provided with an opening for the passage of the 65 sheave and with means to engage the mounting frame, a plurality of rearwardly projecting spacers carried by said face plate, tongues on said spacers and slots on the walls of the supporting element to connect 70 the face plate to said supporting element, a rearwardly projecting flexible extension carried by each of a plurality of said spacers and provided with terminal prongs for engagement with the mounting frame, slots 75 on the walls of the supporting element to facilitate the passage of said prongs into engagement with the mounting frame, and means to maintain the sheave and housing elements, when assembled, in proper relative position.

In testimony whereof I have hereunto subscribed my name this 26th day of January 1922.

JAMES H. FOOTE.
